HEATING SYSTEM

Claude G. Bordeaux, Albany, N. Y.

Application May 4, 1933, Serial No. 669,410

2 Claims. (Cl. 237—12.3)

My invention more particularly relates to a vapor heating system which is particularly applicable to vehicles propelled by internal combustion engines, although it is not limited thereto.

5 The general objects of my invention are to provide a vapor heating system which is simple and compact and which has a quick and effective heat radiation as compared with systems installed in the circulating system connected with 10 the radiator and with the cylinder jacket which have hitherto been proposed.

Another object of my invention is the provision of an unobstructed circulating system including a steam generator and a radiator operating at a predetermined pressure with associated means for introducing water into the system and maintaining a substantially constant quantity.

Other objects of my invention will appear in 20 the specification and will be particularly pointed out in the claims.

My invention will best be understood by reference to the accompanying drawing in which—

Fig. 1 is a side elevation of a device embodying my invention;

Fig. 2 is a perspective view of the vapor generator;

Fig. 3 is a longitudinal sectional view of a check valve;

30 Fig. 4 is a sectional view illustrating a valve located in the by-pass around said check valve, and

Fig. 5 is a view similar to Fig. 4 illustrating a modified form in the by-pass.

35 Like reference characters indicate like parts throughout the drawing.

Referring to the drawing 10 is an internal combustion engine of a vehicle in connection with which I have illustrated my invention. A radiator 11 is connected to the water jacket of the engine by suitable connections 12 and 13. An exhaust pipe 14 leads from the engine in the usual manner.

A circulating system indicated generally at 15 45 comprises a vapor generator indicated generally at 16 and a radiator 17 which may be if desired the ordinary hot water radiator that has commonly been used on vehicles. The vapor generator is preferably formed with a loop 18 which 50 is located in the exhaust pipe 14, the ends 181 and 182 preferably being threaded as illustrated and each provided with a flange 19. The bent ends 181 and 182 of the pipe forming the generator pass through openings 20 in the exhaust 55 pipe as best shown in Fig. 2, a union 21 connecting one end 181 of the generator to a pipe 22 which passes through a wall 23 of the body of the car and connects to the radiator 17. The return of the circulating system comprises the pipe 60 24, leading from the radiator 17 to an enlarge-

ment 28 in the pipe 25 which connects said enlargement to the other end 182 of the generator pipe. A union similar to that above described is preferably used to connect the pipe 25 to the end 182 of the generator.

5 Liquid is supplied to the circulating system through a pipe 26 which may be connected at any suitable point to the water cooling system of the motor. In the embodiment illustrated, the pipe 26 is connected at 27 to the water jacket which 10 forms a part of the water circulating system of the motor. The other end of the pipe communicates with the circulating system 15.

A check valve 38 is located in the pipe 26. A by-pass indicated generally at 39 is connected 15 to the pipe 26 on opposite sides of said check valve. A pipe connection 34 (Fig. 4) is threaded into the casing 311 of the pop valve 31 and the inner end thereof provides a seat for a valve member 35 which is preferably generally cylindrical in form, but provided at its side with longitudinally extending grooves 36. The valve member 35 is normally depressed against the nipple connection 34 by a spring 37 which is designed to be compressed when a predetermined 25 pressure, for example, ten pounds, has been exceeded within the pipe 25 which forms a part of the circulating system.

The operation of my heating system and the 30 elements included therein is as follows. Assuming that the motor of a vehicle with which my device is connected is not in operation, water will substantially fill my heating system, the water flowing from the water cooling system of the motor through the pipe 26, check valve 38, 35 enlargement 28 and thence into the circulating pipes, vapor generator and radiator included in my heating system. Obviously, water cannot entirely fill the heating system due to the fact that no outlet is provided therein for air, hence the air which is trapped therein will prevent the same from becoming entirely flooded. When the motor is initially started, waste gases or 40 exhaust gases will be conducted from the cylinders of the motor through the exhaust manifold 14 and around the vapor generator 16. The generator, being preferably formed from a material having the characteristics of resistance to corrosion from the exhaust gases and high heat 45 conductivity, will transfer the heat from the exhaust gases to the water therein.

When the motor is started, the pump which 50 circulates liquid through the radiator of the vehicle and the water jacket surrounding the 55 motor is also started thereby creating pressure in the jacket which forces liquid through the pipe connection 26 past the check valve 38 into the circulating system 15 which is then flooded as nearly as may be, the entire flooding of the 60

circulating system being prevented for reasons that have already been presented. The pressure which is created in the water block is practically instantaneous whereas it requires an appreciable time to bring the generator up to a temperature sufficiently high to cause vaporization of the water therein to take place. When the generator vaporizes the liquid therein, a pressure is created in the circulating system and when it reaches ten pounds, the by-pass valve 31 opens thereby permitting fluid from the circulating system of the heater to be forced through the pipe connection 26 into the water jacket, since the pressure therein is below that at which the valve 31 opens. The circulating system is thereby relieved of the excess amount of liquid therein and of the excess pressure. As soon as the pressure in the circulating system falls below ten pounds, the by-pass valve 31 is closed.

It will be understood that when the vehicle on which the heating system is installed stops, the exhaust gases no longer pass over the generator, and when the vehicle stops for any appreciable time, the generator cools and when the car is again started liquid is again forced into the circulating system and the cycle of operation above described is repeated.

The valve 38 is thus used only as an emergency valve for the purpose of relieving the circulating system of excess pressure when the same is flooded with liquid as nearly as it may be and the water in the generator heated thereby creating an excess pressure therein. Under normal operating condition the vehicle may run for an entire trip or for an entire day without the valve 38 being operated, the valve 31 being operated only at the time of starting the vehicle and possibly after the motor has been idling.

The system embodying my invention thus provides a single connection only from the water jacket to the circulating system. It will be evident that my heating system comprising only the one pipe connection leading from the water jacket of the circulating system of the vehicle to the circulating system of the heater is simple and inexpensive as compared with a system comprising two such connections and is more efficient as the liquid is not returned to the water jacket under normal operating conditions as is necessarily the case when the circulating system of the vehicle is included as a part of the heating circulating system. Furthermore, the pressure and therefore the temperature is maintained substantially constant under normal operating conditions thus delivering a substantially constant amount of heat to the vehicle. Furthermore, the system embodying my invention is comparatively simple and compact.

I have illustrated in Fig. 5 a modified form of valve 31a for the by-pass. In the form of valve there illustrated, the valve member 35a is in the form of a plain cylindrical member having a close fit in the valve casing 311a. The outlet pipe 30a for the by-pass is connected to a port 30b which is normally covered by the valve member 35a which is biased to the closed position by the spring 37 as in Fig. 4. In moving over the walls of the cylinder, any dirt or other foreign matter is automatically removed from the walls thereof thereby eliminating the possibility of its interfering with the operation of the valve. Furthermore, any grease or oily substance which

may find its way into the water, forms a seal between the valve member 35a and the walls of the casing 311a.

It is to be understood that the control means which I employ will continuously operate while my heating system is in use. Furthermore, the means which I employ to regulate the admission of water to the heating system and the release of steam therefrom maintain the heating system and the water cooling system of the motor as separate systems, the two being entirely operable in a functional sense independently of each other. The water cooling system is utilized merely as a source of water supply and as a condenser for the excessive steam developed in the heating system. Furthermore, it is to be understood that the heating system is so designed that the excessive steam generated therein and which is exhausted through the water cooling system is negligible as a heating factor of the motor cooling system.

A few of the evident advantages of my invention reside in the fact that it may be easily and quickly installed, requires a negligible amount of liquid, and may be used with hot water radiators of installed systems.

While I have referred to water as the liquid medium employed, I do not limit myself thereto, but may use any fluid which may be suitably used in a motor cooling system and which may be vaporized in a vapor heating system.

While I have described my invention in its preferred embodiments, it is to be understood that the words which I have used are words of description rather than of limitation and that changes within the purview of the appended claims may be made without departing from the true scope and spirit of my invention in its broader aspects.

What I claim is:

1. In a vapor generating and heating system, a source of liquid supply normally under pressure during normal operating conditions, an unobstructed closed circulating system in which the liquid circulates independently of said source of liquid supply and including a vapor generator and a vapor radiator, means providing a single passage between said source of liquid supply and said circulating system, a check valve located in said passage opening toward said circulating system, and a by-pass around said check valve and including a normally closed valve operable to open position in response to a predetermined pressure in said circulating system.

2. In a heating system, a closed circulating system including a vapor generator and a vapor radiator with means providing communication between the two, a source of liquid supply under a pressure which may be higher than that in said circulating system under certain conditions of operation, means defining a passage communicating with said source of liquid supply and with said system, a check valve located in said passage for normally preventing the return of fluid from said system to said passage, a by-pass around said check valve, a valve located in said by-pass, and yielding means for normally retaining said valve closed and operable to an open position in response to a pressure in excess of a predetermined pressure in said system.

CLAUDE G. BORDEAUX.
